PORTABLE REFRIGERATOR

Donald E. Dailey, Center Township, Vanderburgh County, Ind., assignor to Servel, Inc., New York, N. Y., a corporation of Delaware

Application November 12, 1954, Serial No. 33,084

Term of patent 14 years

(Cl. D67—3)

T 19. 1.

T 19. 2.

T 19. 3.

Fig. 1 is a perspective view showing the front, top and one side of a portable refrigerator embodying my new design.

Fig. 2 is a front elevational view, in a reduced scale, of the portable refrigerator shown in Fig. 1; and

Fig. 3 is a side elevational view, in a reduced scale, of the portable refrigerator shown in Figs. 1 and 2.

The back and other side of the portable refrigerator, not shown, are substantially the same as the front and side, respectively, shown in the drawing.

I claim:

The ornamental design for a portable refrigerator, substantially as shown and described
